UNITED STATES PATENT OFFICE.

JOHN L. DAWES, OF PITTSBURGH, PENNSYLVANIA.

DESIGN FOR A DISPLAY LAMP.

Application filed January 23, 1924. Serial No. 8,379. Term of patent 14 years.

To all whom it may concern:

Be it known that I, JOHN L. DAWES, a citizen of the United States, residing at Pittsburgh, county of Allegheny, and State of Pennsylvania, have invented a new, original, and ornamental Design for Display Lamps, of which the following is a specification, reference being had to the accompanying drawings, in which the figure is a perspective view of a display lamp embodying my design.

I claim:

The ornamental design for a display lamp, as shown.

In testimony whereof I have hereunto set my hand.

JOHN L. DAWES.
